UNITED STATES PATENT OFFICE.

GEORGE W. GUY, OF CHICAGO, ILLINOIS.

FIREPLACE.

Application filed January 9, 1925. Serial No. 1,435.

My invention relates to heating and more specifically to an improved radiant heater employing an actual source of radiant heat, and a substantially independent apparent 5 source of heat simulating in appearance an ordinary grate fire.

Among the objects of the invention may be enumerated:

First, to provide an illuminated apparent 10 source of heat and an actual radiant source substantially independent of the apparent source.

Second, to deliver the heat of the actual source substantially without heating the apparent 15 source.

Third, to obtain a relatively instantaneous supply of heat apparently coming from a heat source of large mass.

Fourth, to provide an apparent source 20 with reflector means for localizing the illumination to improve the illusion.

Fifth, to simulate the illumination produced by an ordinary grate fire on the floor or supporting structure.

Sixth, to utilize the heat absorbed by the reflecting surface of the radiant heater efficiently.

Seventh, to provide for symmetrical distribution of heat from one, two or three heat 30 units at the will of the user.

Further objects and advantages of the invention will become apparent as the description proceeds.

In the accompanying drawings:

Fig. 1 is a front elevation of a fireplace unit according to the invention.

Fig. 2 is a plan view of the same partly in section and with parts broken away to show the interior construction.

Fig. 3 is a vertical transverse section.

Fig. 4 is a side elevation.

Fig. 5 is a section similar to Fig. 3 showing a modified form of heat reflector.

Fig. 6 is a section similar to Fig. 3 showing an alternative formation of the heat and light reflectors.

In the embodiment of the invention selected for illustration in Figs. 1 to 4, inclusive, the corner posts 10 support a lower front 50 grille 12 and grate bars 14 above the same preferably but not necessarily cast integral therewith, and are suitably attached as at 16 to side plates 18 having horizontal upper portions 20 extending back from the tops 55 of posts 10. Side plates 18 carry lugs 22 at their rear edges for suitable attachment to

corresponding lugs on the side wings 24 of the rear panel 26, which panel has feet 28 extending down to the plane of feet 30 on posts 10 to provide a four point support for 60 the entire frame. Ornamental vases or finials 29 are preferably positioned at the upper ends of posts 10 and the upper corners of the rear panel, the central portion of which panel may also preferably be decorated 65 by suitable scroll work 31.

Bottom plate 32 is supported in any suitable or preferred way, as on grille 12 and end plates 18, or it may be formed integral with the end plates. It carries means for illuminating the lower or apparent heat source such as a pair of spaced sockets 34 equipped with ordinary light bulbs 36. In lateral alignment with lights 36 I prefer to form a plurality of slots 38 through which 70 the light from the bulbs will shine on the floor supporting the structure in such a way as to illuminate a pattern similar to that illuminated by an ordinary grate fire shining through the grate bars. 75

A coarse mesh wire screen extends upwardly as at 39 spaced back of grate bars 14 and then rearwardly at 40 over lights 36. On top of this screen lies a layer of large pieces 42 of colored glass, or other suitable 80 light diffusing material, to produce the appearance of a pile of glowing coals.

Standards 44, one on each socket 34, carry light rotatable fans 46 which are rotated slowly in the warm air currents rising from 85 lamps 36 and produce a flicker not unlike the flicker of flames from such a mass of coals.

By placing downward projections 47 on some but not all of the blades of the fans, the irregularity of the flicker may be made such as to materially improve the lifelike appearance of the whole. These projections will also carry the flicker down in the front of the grate as well as at the top. 90

To further increase the accuracy of the imitation I provide a reflector 48 of suitable material, such as polished tin. By varying the curvature of this reflector a number of different pleasing effects may be obtained. Thus the reflector of Fig. 3 directs most of the light toward the upper portion of the imitation pile of coals, whereas reflector 50 of Fig. 6 will locate the apparent center of the fire lower and farther forward, the upper rear edge of the reflector being suitably attached to the lower flange of an upper reflector 52, preferably of polished copper, the 105

rear edge of the screen being also attached at this point. Above this point I position the actual source of radiant heat, comprising a central heater 54 and side heaters 56 detachably mounted like ordinary incandescent electric lights in sockets 58. The wiring for energizing the sockets is preferably enclosed in a vertical tube 60 extending up the back of the rear panel and lateral tubular shields 62 terminating in end boxes 64 housing the sockets 58 for the side heaters. It will be obvious that, if desired, more than one such heater could be mounted on the central panel. As the heaters may be inserted in sockets 58 by simply screwing them in place, the user may remove one or more of the same when they are cold. Alternatively the units can be made up with only the number desired by the purchaser. A three stage switch 65 may be provided for convenient control in service. It should be noted that either the central heat unit by itself, the wing units together, or all three units together, will in each instance deliver a symmetrical heat effect.

Reflector 52 is spaced from the rear panel 26, as by spacing strips 66. In the embodiment of Fig. 3 it extends vertically up to the central socket 58 and then curves forward and down again to form a dome 68 over the end units. By varying slightly the positioning and curvatures of the reflector a considerable variation in the distribution of heat can be obtained. Thus the shape 35 shown in Fig. 3 will direct the bulk of the heat very close to the front of the device, a considerable portion of it impinging in the first instance on the imitation coal bed 42. The arrangement below the heater in 40 both Figs. 5 and 6 will direct a much larger portion of the radiation from the heater by a single reflection out into the room in front of the fire place. The dome 70 of Fig. 6 will distribute its reflected heat more or less 45 uniformly, some of it being reflected down into the imitation grate and a considerable portion being reflected back to the reflector below the heater and then out into the room, whereas the dome of Fig. 5 will still further 50 shift the distribution away from the grate, the rear portion 72 reflecting directly in front of the grate and the front portion 74 reflecting almost entirely back to the lower portion 76. 55 The best reflecting surfaces that can be obtained for the radiant heat will absorb a material fraction of the heat impinging on them, and even the lower light reflecting screens 48 and 50 will be slightly warmed. 60 To deliver as much as possible of this heat in a convenient, usable form, the space at 78 is provided, continued by the clearance at 80 between the dome 68 and the forwardly arched portion 82 of the rear panel. A 65 hood 84 extends outwardly and downwardly

from the front edge of the panel portion 82 substantially to the level of the heat units. This protects persons in the room from direct exposure to the radiation of the unit itself, and as the hood will not get dangerously hot in use, it protects the users from accidental injuries that might result from touching dome 68 which will often be hot enough to burn the hand severely. The hot air entering space 80 has come up back of 75 the gently heated reflector 48 and the strongly heated reflector 52 and it may pass over the strongly heated dome 68 and down under the front edge of the hood 84, where it affords a very pleasant means of warming 80 one's hands. Incidentally the circulation thus set up keeps the reflecting screen at a somewhat lower temperature and materially improves the efficiency of the heat transfer from the heat unit to the room and its contents. 85

Without further elaboration, the foregoing will so fully explain the gist of my invention, that others may, by applying current knowledge, readily adapt the same for 90 use under various conditions of service without eliminating certain features which may properly be said to constitute the essential items of novelty involved, which items are intended to be defined and secured to me by 95 the following claims.

I claim:—

1. A fire place unit comprising an illuminated imitation grate, a source of radiant heat above said grate, a continuously curved reflector below said source set to reflect radiant heat out over the top of said grate, a reflecting hood above said source, said hood comprising a first portion adjacent the source set to reflect directly out over said 100 grate and a second portion remote from said source set to reflect back onto the reflector below said source, and a second hood spaced over said first hood to define an air passage. 110

2. A fire place unit comprising an illuminated imitation grate, a source of radiant heat above said grate, a continuously curved reflector below said source set to reflect radiant heat out over the top of said grate, a 115 reflecting hood above said source, said hood comprising a first portion adjacent the source set to reflect directly out over said grate, and a second portion remote from said source set to reflect back onto the reflector below said source. 120

3. A fireplace unit comprising a radiant source, a first reflector means for reflecting some of the radiation from said source directly into the space to be heated, and a 125 second reflector means for reflecting other portions of said radiation twice to deliver them to the same space, said second reflector means including portions of said first reflector means. 130

4. A fireplace unit comprising a radiant source, a first reflector means for reflecting some of the radiation from said source directly into the space to be heated, and a second reflector means for reflecting other portions of said radiation twice to deliver them to the same space.

5. A fireplace unit comprising a light source, a heat source above said light source, a reflector behind each source, said reflectors curving forward between said sources, a fo-
10 raminated support extending in front of and above said light source, and means for

attaching the adjacent edges of said reflectors and support to each other.

15

6. A fireplace unit comprising a light source, a heat source above said light source, a reflector behind each source, and a reflector above said heat source shaped to throw a substantial radiation from said heat source and a substantial illumination from said light source down and back onto the reflector behind said heat source.

20

In witness whereof, I hereunto subscribe my name this 5th day of January, 1925.

GEORGE W. GUY.
